C. P. AND F. E. HOWARD.

DOOR HOLDER.

APPLICATION FILED JAN. 22, 1919.

1,390,786.

Patented Sept. 13, 1921.

UNITED STATES PATENT OFFICE.

CHARLES P. HOWARD AND FRANK E. HOWARD, OF HARTFORD, CONNECTICUT,
ASSIGNORS TO JAMES L. HOWARD & COMPANY, OF HARTFORD, CONNECTICUT, A CORPORATION OF CONNECTICUT.

DOOR-HOLDER.

1,390,786.

Specification of Letters Patent. Patented Sept. 13, 1921.

Application filed January 22, 1919. Serial No. 272,581.

To all whom it may concern:

Be it known that we, CHARLES P. HOWARD and FRANK E. HOWARD, citizens of the United States, and residents of Hartford, in the county of Hartford and State of Connecticut, have invented certain new and useful Improvements in Door-Holders, of which the following is a full, clear, and exact specification.

This invention relates to a door stop and holder, and operating mechanism therefor, and is particularly applicable to the doors of railway cars and other conveyances.

The object of the invention is to provide substantially inclosed holding devices that will arrest the movements of a door, and particularly of a sliding door, either in its full open or closed positions or at any point in its travel, thereby eliminating the liability of injury to passers by, or of damage to the door or its mechanism by its exposure or by slamming action due to sudden forward or swaying motions, such as occur in railway cars, ships, and other conveyances.

A further object of the invention is to connect or coördinate the holding device with the door operating or latch operating means, so that the door is automatically seized by and released from the holder by the ordinary operations of moving the door, without requiring conscious effort or attention of the operator being directed to the operation, or even to the existence of the inclosed and partially or wholly concealed holding devices.

In prior devices of this class, the arresting or holding means have usually been applied above or below the door, considerably at one side of the path of movement of the center of the mass or weight of the door, thus setting up a violent shock when the door is stopped due to the continued swinging movement of the free end of the door. In the present invention, this objection is avoided by placing the holding devices between the ends of the door and preferably at or near the horizontal path of movement of the center of the mass or weight of the door.

Broadly speaking, the invention herein disclosed comprises a substantially inclosed door holder controlled by an operating han-

dle of the door, whereby the ordinary and normal operation of a door handle or latch lever releases the door from the holder, and permits movement of the door and whereby releasing or turning back the handle or lever causes or allows the holder to arrest the movement of the door and hold it stationary.

The invention is adaptable for stopping and holding doors either positively, or more yieldingly by frictional action. The particular embodiment illustrated in the accompanying drawings employs frictional or braking action. It consists of a casing or frame carried within or upon the outer side of the door and within which is mounted for reciprocatory movement a brake rod, one end of which is connected to the door operating handle, and the other end of which, by a suitable cam element, coöperates with a brake carried by the casing. A stationary brake bar connected with the door jamb or frame coöperates with the braking mechanism by the movements of the door operating handle. The construction and association of the parts is such that when it is desired to move the door in either direction the operating handle is moved in that direction. This movement causes the brake to be released, whereupon the door is free to move. Releasing the door handle allows the brake to be applied, thus stopping and holding the door at any desired position.

Figure 1 of the drawings is a fragmentary side view, partly in section, of a sliding door having this invention applied.

Fig. 2 is a plan view projected from Fig. 1 showing the door in section.

Fig. 3 is an end view of the brake mechanism carried by the door, the brake bar being shown in section.

Fig. 4 is fragmentary plan view of the brake bar.

Figs. 5 and 6 are elevations partly in section, of the neutralizing device.

Fig. 5 shows the position in which the door handle is held in its neutral position of Fig. 1, with the brake applied, while Fig. 6 shows the position of a part of the neutralizing device when the door operating handle is moved toward the right, and the brake is released.

Fig. 7 is an end elevation, in transverse

section on the line 7—7 of Fig. 1, looking in the direction of the arrows. Fig. 8 is a similar view, taken on the line 8—8 of Fig. 1.

Fig. 9 is a transverse section on the line 5 9—9 of Fig. 5, looking in the direction of the arrows.

Fig. 10 is a transverse section on the line 10—10 of Fig. 1, looking in the direction of the arrows.

10 Fig. 11 shows a modified cam arrangement in reduced scale.

Referring to Fig. 1, the stationary door frame of a car or other structure is indicated at 1, with the sliding door in full open position 15 and held by the brake.

Carried by the lock-stile 2 of the door in any suitable manner is a door locking or latching mechanism, comprising the latch 4, the tumbler 5, and the operating handle 6, 20 by which through the squared spindle 7, the latch mechanism is operated and the door opened and closed. This latch mechanism is of the general character shown in U. S. Patent 720,349 of Feb. 10, 1903, but the invention is applicable to practically any door latch or lock mechanism, or to a door 25 without such mechanism.

Projecting downwardly from the latch mechanism and carried by the spindle 7 is an operating lever 8 terminating at its lower 30 end in a pin 9, or other suitable connection by which the braking mechanism is operated.

Mounted within or carried by the rail 10 or otherwise supported by the door, is a 35 casing 11 which incloses and supports the brake mechanism. Carried by the side walls 12 and 13 or the casing 11 are ball races 14 and 15, between which are supported by anti-friction balls 16, a sliding cam 17, one 40 end of which is pinned, or suitably connected as at 18, to the inner end of the brake rod 19. The outer end of the brake rod 19 is articulated with the lower end of the operating lever 8 by the yoke 20, which forms a 45 sliding pivotal connection between the operating handle and the brake rod. For the purpose of guiding the brake rod in its lateral movement, guides 21 and 22 (Fig. 5) are fixed to the casing 11 and are so spaced 50 that they also form abutments for the neutralizing device hereafter more fully described.

Attached to the rear edge of the door and adjacent to the rear edge of the casing 1, is 55 a bracket 23, the upper and rear end of which terminates in a lug 24 which may carry, by means of screws 25 and the plate 26, a buffer 27 of rubber or similar material, to cushion the impact of the door when 60 moved to its full open position.

Pivoted as at 28 in the slots 29 of the bifurcated rear edge of the bracket 23, is the brake lever 30, the front or inner end of which is bifurcated and carries a roller 31

which is adapted to engage with the sliding cam 17. Intermediate the ends of the brake lever there is carried preferably by means of a pivot pin 32, the brake shoe 33 which is raised and lowered by the brake lever out of and into contact with the brake bar 34. 65 70

One end of the brake bar 34 is supported as at 36, preferably by a pivoted connection with the bracket 37, which is fast to the stationary door frame 1. The other end of the brake bar projects forwardly and preferably lies within the casing 11, and is supported by the bottom 35 thereof, (Fig. 1). This support may be utilized as a brake element for the bar. The brake bar is of such a length that when the door assumes a closed position, a portion of the bar will still extend beneath the brake shoe, and when the door assumes a full open position, as shown in Fig. 1, the outer end of the bar will not project beyond the lock-stile 2 of the door. 75 80 85

The brake shoe may be removed from the brake lever for renewal or repairs by removing pivot pin 32 from the brake lever, after pulling upwardly on the finger 39, which projects upwardly from the rear end 90 of the brake lever 30, thus exposing the ends of the pin 32 above the retaining ears 40, formed on the bracket, which under working conditions retains the pin 32 in place.

A spring 38 disposed between the bracket 95 23 and brake lever 30, presses the brake shoe 33 against the brake bar 34 when the brake is applied.

The application and release of the brake are controlled by the cam 17, the working 100 face of which is disposed below the roll 31, and works against the downward thrust of the spring 38. The cam contour includes a recess 41, which is brought beneath the roll to allow the brake to be applied as shown in 105 Fig. 1. Movement of the cam away from this position brings an inclined side of the recess into contact with the roller 31, thereby raising the brake shoe from the bar 34, releasing the door for movement, and bringing the level contour 42 of the cam beneath the roller, where it rests during the movement of the door, after which by moving the cam it is returned to neutral position, bringing the recess 41 again beneath the roller. For 110 thus returning the cam to its neutral or braking position, which in the double acting construction herein illustrated is its central position, what is herein termed a neutralizing or centralizing device is employed. 115 It is herein shown (Figs. 5 and 6) as being applied directly to the brake rod 19, although it may be applied to any other part of the connections between the handle 6 and the cam 17. When that handle is also employed as herein shown, for operating the latch or latches of the door, it is desirable 120 to return the handle to its neutral position 125

in order to leave the latch or latches free to engage with any of their latch or striker plates.

The neutralizing device is carried within the casing 11. A stop 43 is mounted on the casing 11, centrally disposed between the guides 21 and 22. Spring caps 44 and 45 carried by the brake rod 19 are adapted to abut against the stop, under pressure of the expansion springs 46 and 47, surrounding the brake rod 19 and lying between the guides 21 and 22, as shown in Fig. 5. Pinned or fixed to the brake rod 19, between the adjoining caps 44 and 45, is the collar 48, which is substantially of the same width as the stop 43, and is centrally held in the neutral position shown in Fig. 5 by the action of the springs 46 and 47. Endwise movement of the brake rod 19, and of the sliding cam 17 which is attached thereto, in either direction, by the operating handle 6, and its depending lever 8, will move the collar 48 endwise in that direction against the pressure of whichever spring 46 or 47 may thus be compressed. Movement of the cam 17 away from its neutral or braking position is thus opposed in one direction by the spring 46, and in the other direction by the spring 47. The initial movement of the cam in either direction, while releasing the brake against the pressure of its spring 38, by the inclined sides of the cam recess 41, is additionally opposed by reaction of that spring upon the side of the recess. But as soon as either inclined side has passed beyond the point of contact with the roller so that the latter rests upon either the level surfaces 42 of the cam, which are parallel with the direction of the cam movement, the reactive effect of the brake spring 38 upon the cam movement ceases, leaving only the resistance of whichever spring 46 or 47 may be compressed. The tension of the latter spring needs only to be sufficient to return the freely moving cam and its connections to their neutral position when the handle is released, and the continuing pressure on the handle 6, necessary to keep the door moving, is sufficient to overcome that tension, and prevent the cam from being returned to neutral position. But when the handle is released, the cam is returned to neutral position by the action of the compressed spring 46 or 47, as the case may be, augmented at the latter part of its movement by the pressure of the brake spring 38 when the cam has moved far enough to bring the inclined sides of its recess 41 into contact with the roller 31.

In operating this device when arranged as shown in the drawing, the operator grasps the door handle 6 and turns it, preferably in the direction of the desired movement of the door, that being his natural impulse or tend-

ency. This initial turning movement releases the brake, and when connected with a latch as herein shown, it also lifts the latch, and unfastens the door if the latter should be in a latched position. This initial movement requires sufficient effort to overcome first, the resistance of the brake spring 38, and then the inertia of the door. Then the door, being released from the brake and from its latching hold, is moved by a continuation of the pushing action upon the handle until it reaches the desired position, whereupon the operator lets go of the handle, thus allowing it to return to its neutral position, thereby applying the brake and allowing the latch raised or latches to fall. Thus the door may be moved from either direction, through any portion, or the whole of its path of movement.

The brake remains released throughout the entire movement independently of the latch 4 which is free to ride over and fall behind its striker plate, being raised only when the handle 6 is turned to the left to move the door in the opposite direction. The latch is free to make its latching movement without applying the brake.

Stop abutments, limiting the turning movements of the door handle to the range required for operating its latch, or for releasing the brake, are preferably employed, as shown in the patent above referred to. A bar or projection 54 on the door handle 6, travels in a slot 55 in the door, or escutcheon plate, the ends of the slots serving as stops for the handle turning movement and receiving the pressure then applied to move the door.

The parts are herein shown to be arranged and connected so that the door handle 6 is turned in the direction it is desired to move the door, this being the natural and preferable arrangement. Obviously, however, the parts may be otherwise arranged and connected according to circumstances. For example, if the door handle is not connected with a latch, or if the latch connection requires the handle to be turned in the opposite direction, the brake will, nevertheless, be operated correctly, without any change in the connection between the handle and the brake device. Obviously, also, the handle might be extended downwardly or in any direction from the operating spindle 7, or a knob or cross handle might be employed. Such modifications should be adapted to the style or arrangement of the door, or to the preferences of the designer or user of the device.

The cam 17, which is herein shown as being mounted for sliding or rolling reciprocatory movement in a plane, with which the level surfaces 42 are parallel for the reason above described, may as shown in Fig. 11, be a sector shaped cam 50, mounted for

swinging reciprocatory movement in a pivotal center 51 either above or below the roller 31, approximately along the line 7—7, Fig. 1, and pivotally connected with the 5 brake rod 52. The recess in such a cam would be substantially like the recess 41, but the surfaces corresponding with its surfaces 42 should describe circular arcs 53 concentric with the center 51 of oscillation of 10 the cam, thus making these surfaces parallel with their direction of movement, for supporting the roll 31 without reacting upon the cam to turn it to its neutral position while the door is being moved.

15 The coating surfaces of the brake shoe 33, the bar 34, or its support 35, or any of them, may be provided with any approved brake lining material, or otherwise adapted in any approved way as braking surfaces.

20 Or they may be corrugated or notched to increase the holding effect. The holding notches may be arranged at such intervals as may be suitable for holding the door positively in certain predetermined desired position, thus in effect utilizing the brake bar as a striker plate. The brake lever 30 may in that case be provided with a tooth or pawl extension in place of the pivoted brake shoe 33, adapted to enter the notches of the brake bar. Thus the brake lever may be made to serve as a latch, dispensing with the latch 25 4. Other modifications within the province of the designer or builder may be made, to adapt the device to different conditions of service.

The invention claimed is:—

1. The combination with a door and its 30 operating handle, of a substantially inclosed holding device adapted to hold the door at intermediate positions in its movement, including a brake bar extending into a casing carried by the door, a holding device in said 35 casing, and connecting means between the said device and the said handle whereby the latter in the performance of its door moving function also controls the operation of the said inclosed holding device.

2. The combination with a door and its 40 latch mechanism, of a door latch operating handle movable on and with the door, and a substantially inclosed door holding device adapted to hold the door at intermediate positions in its range of movement, including a brake bar extending into the door a coöperating holding device in the door, and connecting means between the said handle and the said holding device, whereby the handle by its normal latch 45 operating movements also controls the operation of the holding device during either of said movements.

3. The combination with a door, of a holding device for the door, including a holding element extending along and within the path

of the door movement, engaging devices carried by the door in engaging relation to the said element, including an operating handle mounted for movement on the door in the directions of the door movements and connected with the said engaging devices to operate them at different positions of the door.

4. The combination with a door, of means for holding the door at intermediate positions in its range of movement, including coöperating holding members, a movable cam for operating one of said members, having an operating surface inclined to its direction of movement, and a retaining surface substantially parallel to that direction, and means for moving and retracting the 80 cam.

5. The combination with a door of means for holding the door at intermediate positions in its range of movement, including coöperating holding members, a double acting cam for operating one of said members having a substantially V shaped surface, the sides of which, when in neutral position, are disposed on opposite sides of the co-engaging portion of said member, means for moving the cam in either direction, and means for returning the cam to neutral position.

6. The combination with a door of means for holding the door at intermediate positions in its range of movement, including coöperating holding members, a double acting cam for operating one of said members having a substantially V shaped surface, the sides of which, when in neutral position, are disposed on opposite sides of the co-engaging portion of said member, means for moving the cam in either direction, an operating handle connected with the cam and mounted for movement on the door in both directions of the door movement, and resilient means 100 for returning the cam to neutral position.

7. The combination with a sliding door and its latching devices, of holding means for holding the door when away from its latching position, and operating connection 110 between the said latching devices and said holding means, to operate them correlatively but independently of each other.

8. The combination with a sliding door and its latching mechanism, of holding devices for unlatched positions of the door, including an element disposed along the pathway of the door movement, and connecting means between the latching mechanism and the holding means for operating them coincidentally, to release the door, and operating the holding device independently 115 to hold the door.

9. The combination with a door braking mechanism and a door handle adapted to 125 operate the door and the braking mechanism, of independent resilient means actuating the braking mechanism and returning the door

handle to inoperative position when the door handle is released.

10. Braking mechanism for a door, comprising a brake bar extending into the door, a brake shoe within the door adapted to co-operate with the brake bar, an operating handle, connections between the operating handle and the brake shoe, means for operating the brake shoe to disengage it from the brake bar by a movement of the handle in either direction, and means for applying the brake upon the return of the handle to neutral position.

11. In braking mechanism for a sliding door the combination of a brake shoe, and a brake bar disposed between the ends of the door and adapted to be engaged at times with each other, an operating handle, and independent means associated with the brake shoe and operating handle for applying the brake and moving the handle to a neutral position when released.

12. In braking mechanism for a sliding door, the combination of a door operating handle, a brake lever and a brake shoe carried thereby, a brake rod connected to the handle and co-operating with the brake lever, and independent resilient means acting upon the brake rod to move the handle to neutral position, and operating the brake lever to apply the brake shoe.

13. In braking mechanism for a sliding door, the combination of a brake lever carrying a brake shoe, a spring acting upon the brake lever to apply the brake shoe, a cam co-operating with the brake lever, means for actuating the cam to move the brake lever, and means for moving the cam to permit the spring action to move the brake lever and apply the brake shoe.

14. The combination with a door, of a spring pressed holding device therefor, and actuating means for the holding device, including a reciprocatory cam having a portion of its surface inclined to its direction of movement for actuating the holding device, and having an adjacent portion of its surface substantially parallel with that direction to avoid reactive operation by the holding device upon the cam movement. 45

15. The combination with a door, of a holding device therefor including a spring for moving a holding member of the device, and a reciprocatory cam for moving the said member against the pressure of its spring, the cam having in its actuating surface a recess to permit free movement of the holding member by its spring, a side of the recess being inclined to its direction of movement to actuate the holding member, and having a 60 surface substantially parallel with that direction to prevent reactive effect of the spring on the cam movement. 50

16. The combination with a door, of a holding device therefor including a spring 65 for moving a holding member of the device, and a reciprocatory cam for moving the said member against the action of its spring, the cam having in its actuating surface a recess to permit free movement of the holding member by its spring, the sides of the recess being inclined to their direction of movement to actuate the holding member by movement of the cam in either direction, and having surfaces substantially parallel 75 to the direction of that movement to prevent reactive effect of the spring on the cam movement. 70

CHARLES P. HOWARD.
FRANK E. HOWARD.

It is hereby certified that in Letters Patent No. 1,390,786, granted September 13, 1921, upon the application of Charles P. Howard and Frank E. Howard, of Hartford, Connecticut, for an improvement in "Door-Holders," errors appear in the printed specification requiring correction as follows: Page 3, line 80, for the words "latch raised" read *raised latch*; page 4, line 49, claim 2, strike out the word "door"; and that the said Letters Patent should be read with these corrections therein that the same may conform to the record of the case in the Patent Office.

Signed and sealed this 18th day of October, A. D., 1921.

[SEAL.]

KARL FENNING,

Acting Commissioner of Patents.
